DESIGN FOR A JEWELRY BOX OR SIMILAR ARTICLE

Reuben Parness, Brooklyn, and Samuel Sweet,
Bronx, N. Y.

Application October 5, 1934, Serial No. 53,500

Term of patent 3½ years

To all whom it may concern:

Be it known that Reuben Parness, a citizen of the United States, residing at Brooklyn, in the county of Kings and State of New York, and Samuel Sweet, a citizen of the United States, residing at Bronx, in the county of Bronx and State of New York, have invented a new, original, and ornamental Design for a Jewelry Box, or Similar Article, of which the following is a specification.

In the accompanying drawing:—

Fig. 1 is a perspective view of a jewelry box or similar article in a closed position, showing the design.

Fig. 2 is a perspective view of the jewelry box shown in Fig. 1 in an open position.

Fig. 3 is an end elevational view of the jewelry box shown in Fig. 1.

The dominant feature of the design is the slightly projecting top and bottom bases on the top and bottom sides of the box within the area of the sides thereof and congruent with the top and bottom shapes.

We claim:—

The ornamental design for a jewelry box or similar article as shown and described.

REUBEN PARNESS.
SAMUEL SWEET.
